UNITED STATES PATENT OFFICE.

GEORGE C. NELSON, OF PETERSHAM, MASSACHUSETTS.

IMPROVEMENT IN PLAITING-MACHINES.

Specification forming part of Letters Patent No. 40,424, dated October 27, 1863.

To all whom it may concern:

Be it known that I, GEORGE C. NELSON, a resident of Petersham, in the county of Worcester and State of Massachusetts, have invented a new and useful Machine for Plaiting the Crowns of Shaker Bonnets; and I do hereby declare the same to be fully described in the following specification and represented in the accompanying drawings, of which—

Figure 1 is a top view, Fig. 2 a side elevation, and Fig. 3 a longitudinal section, of the said machine. Fig. 4 is a top view of the plaiting-block or plait-former.

It is a fact well known to those engaged in the manufacture of what are termed "Shaker bonnets" that the plaiting of the crowns of such bonnets has hitherto been accomplished by hand, and that such is a slow and tedious operation. To find a better and more ready means of attaining this result—viz, the plaiting of the crowns of such bonnets—has been the object of my invention.

The nature of my said invention consists, first, in the combination of a plaiting-former with a series of plaiting-jaws, the same being arranged and so as to operate together substantially as hereinafter set forth; and my invention further consists in combining with the plaiting-former and its plaiting-jaws an elevating-frame or its equivalent.

In the said drawings, A denotes a rectangular frame or box for supporting the operative parts of the machine. On the top of the said frame A the mold or mechanism for imparting to the crown the desired width and inclination of the line of plaits is disposed, such mechanism being a series of metallic plates, *a b c*, &c., corresponding in number with the number of plaits to be made in the crown. *a* is the upper and narrowest one of the series *b* and *c*, being of greater width and arranged, respectively, below the same, as shown in Figs. 2 and 3. On the plate *a* the crown-piece is placed preparatory to being operated upon, and is held in position thereon by a holder or bar, *G*, affixed to the plates *B B*, hereinafter mentioned. Under each edge of the several plates a groove or channel, *g* or *g'*, is formed, the same being to receive a series of plaiting-jaws or crimpers, *h h i k k*, and such jaws when in use are caused to operate consecutively in pairs. Each half of each pair of the crimpers is sup-

ported by two journals, *l l*, extending horizontally from its opposite ends, and into bearings formed in the plates *B B*, suspended from the inner face of the frame *C*, which is arranged over the box *A*, as shown in Figs. 1 and 2. Each of the crimping or plaiting jaws has its lower part bent inward at or about at a right angle to its main face, as seen in the drawings, such lower portion being of a trapezoidal or such other shape as will conform to the channel formed under the lower edge of the plate, with which it is intended to operate. Furthermore, there projects at right angles from the outer face of each crimper or plaiting-jaw a lever, *m*, the same having an eye, *t*, formed on its outer extremity, to which a link, *n*, is connected, the said link in its turn being united with the outer end of one arm of a curved spring, *o*. The middle part of the said spring is soldered or otherwise properly secured to a bar, *D*, which extends transversely across the frame *C*, as seen in Fig. 1. The object of this two-armed spring is to retract the plaiting-jaws or crimpers and elevate them to their highest positions after they may have performed their proper functions. There is also jointed to the outer extremities of each pair of the levers *m* a connecting-rod, *p*, to whose lower ends any suitable mechanism may be applied, such as will cause each pair of the plaiting-jaws to be consecutively drawn or caused to fall downward, so as to evenly and smoothly fold the crown-piece with the desired number of plaits. This mechanism may be a series of weights, one or more being attached to each pair of the arms *m*, and so arranged upon a platform disposed beneath them that when such platform may be depressed each set of arms *m* shall be so acted upon at the proper period of time as to force the sets of crimping-jaws consecutively into the grooves formed to receive them.

For the purpose of allowing the frame *C* to be elevated whenever it may be necessary, I form the lower portion of the legs *s s s s* of said frame of a less diameter than the upper part, and extend such lower portions down through mortises or holes made in the frame *A*. The cylindrical shoulders thus made on the said legs serve to retain the frame *C* in its proper position with respect to the frame *A* when the machine may be in use. By sim-

ply taking hold of the frame C it may be easily raised from the frame A, as circumstances may require.

Having described the construction of my said invention, I will now describe its operation.

If we suppose the parts to be in the positions represented in the drawings, we first raise the frame C a sufficient distance to allow the crown-piece to be introduced flatwise between the plate *a* and bar *G*. We next cause the frame C to descend until the plate or bar *G* shall rest upon the middle part of the crown-blank and firmly hold it in its proper position while the crown is being plaited. Next, we so operate on the mechanism employed to bring the several sets of jaws consecutively into action upon the crown-piece, as to cause the first pair of jaws *h h* to act upon or force portions of the free ends of the said crown-piece into the groove *g* or *g'*, and thereby form the underlap or fold. This having been done, we next cause the second set of jaws, *i i*, to be brought into operation and to act upon another portion of

the crown-piece in like manner as that just described. Thus we continue the operation with each set of jaws in succession until all the plaits have been made in the crown. We next remove the downward pressure on the sets of jaws, and the springs *o o*, &c., cause the several sets of jaws to be drawn asunder. Next, by raising the frame C a short distance the crown can be readily drawn from the machine.

I claim—

1. The combination of the plaiting-former and its series of plaiting-jaws, the whole being arranged in manner and so as to operate together substantially as described.
2. The combination of the elevating-frame or its equivalent with the plaiting-jaws and their former.

GEORGE C. NELSON.
